UNITED STATES PATENT OFFICE.

GEORGE B. EBERENZ AND JAMES I. BROWN, OF CRIPPLE CREEK, COLORADO.

ORE-CONCENTRATOR.

1,187,822.

Specification of Letters Patent. Patented June 20, 1916.

Application filed March 2, 1916. Serial No. 81,582.

To all whom it may concern:

Be it known that we, GEORGE B. EBERENZ and JAMES I. BROWN, citizens of the United States, residing at Cripple Creek, in the 5 county of Teller and State of Colorado, have invented certain new and useful Improvements in Ore-Concentrators, of which the following is a specification, reference being had to the accompanying drawings.

10 This invention relates to ore concentrators of that class where the ore is concentrated by gaseous flotation of mineral particles in liquid. In all concentrating apparatus known to us carrying out the flotation principle, the finely ground ore, together with water and the frothing agent such as oil, is driven from an agitating tank or compartment into the spitzkasten and from the spitzkasten passes into another agitating 15 tank. Furthermore, in all flotation concentrating apparatus known to us, the liquid with the finely ground ore and the frothing agent is agitated and driven into the spitzkasten by means of impeller blades operating 20 in a horizontal plane.

We have found by careful practical demonstrations that horizontally operating agitating blades do not bring the finely ground ore into thorough contact with the air and 25 frothing agent, and one of the objects of the invention is to improve upon constructions of this character by the provision of agitating blades which move in a vertical plane, and in this connection to provide a 30 spitzkasten so connected with the agitating chamber, vessel or tank that the finely ground ore and liquid will be driven into the lower end of the spitzkasten and then sucked back into the agitating tank over the 35 top of the agitating blades whereby more air is beaten into and mixed with the mass in the agitating tank and the whole mass returned again and again to the spitzkasten where the concentrates rise and pass off 40 until the separation of the concentrates from the gangue is complete.

The invention is illustrated in the accompanying drawings, wherein:

Figure 1 is a top plan view of a concentrating apparatus constructed in accordance with our invention; Fig. 2 is a section on the line 2—2 of Fig. 1; and Fig. 3 is a section on the line 3—3 of Fig. 2; Fig. 4 is a sectional view showing the manner in which 50 apparatus with horizontally revolving blades operates.

Referring to these drawings it will be seen that our improved concentrator comprises the agitating tank 10, having at its lower end the tailings discharge 11. The 50 spitzkasten 12 has the usual outwardly and upwardly extending wall 13 which at its upper end is provided with the apron 14 discharging into a launder 15. The wall 16 dividing the agitating tank from the 55 spitzkasten is formed with a longitudinally extending opening 17 disposed above the lower end of the wall, and at the base the wall 16 is also formed with a longitudinally extending opening 18. It will be noted that 70 the wall 16, below the opening 17, is formed with a portion 19 projecting into the agitating tank 10.

Mounted within the agitating tank and extending longitudinally therethrough is a 75 shaft 20, and mounted upon this shaft are impellers or agitators which rotate in a vertical plane. As illustrated, these impellers comprise the collars or heads 21 having radial arms 22, each of these arms carrying 80 a plurality of spaced blades 23. The diameter of the agitator or impeller across the blades is nearly equal to the width of the agitating tank 10. The shaft 20 passes out through suitable stuffing boxes 24 carried by 85 the side walls of the agitating tank, and the shaft is connected to any suitable driving mechanism, as by means of the belt wheels or drive pulleys 25.

It will be noted in Fig. 2 that the impeller 90 or agitator is disposed slightly below the opening 17 and that its blades in their travel extend down to a point approximately opposite the opening 18. It will be seen that the impeller, as illustrated, has a 95 plurality of horizontal vanes carrying blades, and that there are spaces between the blades, and we have found in practice that these spaced blades assure the greatest possible amount of agitation, emulsifying 100 and beating of the air and oil into the mass and bringing the finely crushed ore into intimate contact with the air, water and frothing agent. The mass so intermingled and mixed is driven from the cell or chamber 10 into the spitzkasten through the opening 18, and in the spitzkasten the concentrates separate and come to the top in the form of froth. This froth passes off 110 over the apron 14 and is discharged into the launder 15, while the tailings or gangue in the spitzkasten returns to the cell 10 through

the opening 17 and is subjected to further agitation so that the mineral particles which have not been subjected to the action of the oil and froth will then come in contact therewith and will be raised when they once more pass into the spitzkasten.

In our construction there is one continual circulation of emulsion from the agitating chamber or cell into the spitzkasten and back again. This constant circulation of the mass is secured by the vertically rotating impeller or agitator which gives a circulation from the bottom of the cell 10 into the bottom of the spitzkasten and then back into the cell through the openings 17 and over the top of the impeller. Here more air is beaten and churned into the mass and a better intermingling of the elements is secured and the whole mass again returned to the spitzkasten. This operation is carried on until the concentrates have been entirely raised and passed off, when the tailings are drawn off through the tailings discharge.

With this invention it is not necessary to pass the mass from one agitating chamber into the spitzkasten, then into a second agitating chamber and again into a spitzkasten, and so on, but one agitating chamber and one spitzkasten is all that is necessary for the complete separation of the concentrates from the gangue. Of course, it will be obvious that we may build the agitating cells or tanks and the spitzkasten in batteries, but the prime object of our invention is to do away with the necessity of passing the material through a series of agitating cells and the spitzkasten, and confine the operation to one cell and one spitzkasten.

While we have shown certain details of construction, it is obvious that many changes might be made without departing from the spirit of the invention. It is to be particularly noted that the agitator does not operate merely to throw the materials out from the agitator, but it operates to churn up the materials and intimately intermingle the pulp with the oil and air, and further, it will be noted that the mineral particles that do not come in contact with the oil at the first agitation are carried back from the spitzkasten into the agitating chamber or cell and there again subjected to the action of the agitator. In practical operation it has been found that our apparatus will make sufficient froth through the action of the agitator so that no frothing oils are necessary. It will be obvious, of course, that the dimensions of the agitation chamber and the spitzkasten will vary, depending upon the amount of work required, but that in all cases the agitating blades will have a length nearly equal that of the agitation chamber. After the separation of the mineral from the pulp has been secured, the tailings are drawn from the bottom of the agitation

chamber and the agitation chamber is again recharged and the operation repeated.

In the practical operation of this invention the cell and spitzkasten are filled with water to the amount required, then the pulp is added and after a little agitation a small amount of oil is added. The oil required is of a very small quantity and much less than in other machines because of the violent agitation to which the liquid and pulp in the cell are submitted. After the oil is added, separation commences to take place immediately. This machine gives a violent agitation to the liquid, which is necessary in order that the oil may get into intimate contact with the mineral particles. The water rises in the spitzkasten to the overflow apron, while in the cell it remains barely above the vanes 23 of the impeller thus giving it all the air necessary to create all the froth required to float the mineral particles that are bound to come in contact with the oil. The water, pulp and air are all added through the top of the cell which may be left open or partly closed in case the material splashes out.

In Fig. 4 we show a section of an ordinary concentrating machine using the cell and spitzkasten and a horizontally disposed rotatable beater or agitator, and this view shows the manner in which the horizontally rotating agitator operates. It acts to lower the level of the metal portion of the liquid and the oil, or some of it remains on the top of the cell at the top of the liquid and gets around the walls, that is, on the higher portions surrounding the center of the liquid column. Fig. 2 illustrates the manner in which our machine acts. The vanes of the impeller or agitator are in view at almost all times so that air is thoroughly beaten into the mass and all of the oil and pulp are continually separated.

It is of course to be understood that the openings 17 and 18 are so proportioned as to maintain a liquid level in the agitation chamber lower than that in the spitzkasten.

Having described the invention, what we claim is:

1. An apparatus for concentrating ores by gaseous flotation of mineral particles in liquid, including an agitating tank and a spitzkasten, the agitating tank having an opening at its base leading into the base of the spitzkasten and an opening leading from the spitzkasten and into the agitating chamber above the base and below the overflow level of the spitzkasten, and an agitator rotating in a vertical plane within the agitating tank and disposed below the plane of the second-named opening, the agitator rotating in such a direction as to draw liquid inward into the agitating tank from the spitzkasten by the upper opening but force liquid from the agitating tank into the

spitzkasten by the lower opening, the upper and lower openings being so proportioned as to maintain a liquid level in the agitating tank lower than that in the spitzkasten.

- 5 2. In an apparatus for concentrating ores by gaseous flotation of mineral particles in liquid, an agitating tank, a spitzkasten in conjunction therewith, the agitating tank opening its base into the base of the spitzkasten and there being an opening above the base between the spitzkasten and the agitating tank, said opening being below the overflow level of the spitzkasten, and means disposed within the agitating tank for agitating the liquid therein and forcing the liquid into the spitzkasten through the base opening and drawing liquid from the spitzkasten into the agitating tank through the upper opening, said agitating means being disposed below the level of the upper opening, said upper and lower openings being so proportioned as to maintain a liquid level in the agitating tank lower than that in the spitzkasten.
- 10 3. In an apparatus for concentrating ores gaseous flotation of mineral particles in liquid, an agitating tank, a spitzkasten, the tank opening at its base into the base of the spitzkasten, there being an opening from the middle of the agitating tank into the spitzkasten, said opening being below the normal level of the pulp in the spitzkasten, a shaft passing horizontally through the agitating tank and horizontally disposed
- 15 blades mounted on the shaft and rotating in a vertical plane, the shaft and blades being disposed at all times below the second-named opening and the agitator rotating in a direction to cause a circulation of mate-

rial from the agitating tank into the spitzkasten through the first-named opening and back into the agitating tank through the second-named opening, the first and second named openings being so proportioned as to maintain a liquid level in the agitating tank lower than that in the spitzkasten.

4. In an apparatus for concentrating ores by the flotation process, an agitating tank, a spitzkasten, the tank at its base opening into the spitzkasten and there being an opening between the tank and the spitzkasten above the lower opening but below the normal level of the pulp in the spitzkasten, a shaft passing horizontally through the agitating tank parallel to the length of said openings, arms carried upon the shaft, and a plurality of blades connecting said arms and spaced from each other, the arms and blades being below the level of the second-named opening and rotating in a direction to cause pulp to be drawn through the second-named opening from the spitzkasten into the agitating tank and expelled from the agitating tank into the spitzkasten through the first-named opening, the first and second named openings being so proportioned as to maintain a liquid level in the agitating tank lower than that in the spitzkasten.

In testimony whereof we hereunto affix our signatures in the presence of witnesses.
